UNITED STATES PATENT OFFICE.

ANDRIAN I. BARRANOFF, OF BANGOR, MAINE.

STEAM-BOILER.

SPECIFICATION forming part of Letters Patent No. 398,370, dated February 26, 1889.

Application filed July 20, 1888. Serial No. 280,478. (No model.)

To all whom it may concern:

Be it known that I, ANDRIAN I. BARRANOFF, a citizen of the United States, residing at Bangor, in the county of Penobscot and State of Maine, have invented certain new and useful Improvements in Steam - Boilers; and I do hereby declare the following to be a full, clear, and exact description of the invention, such as will enable others skilled in the art 5 to which it appertains to make and use the same, reference being had to the accompanying drawings, and to letters or figures of reference marked thereon, which form a part of this specification.

15 This invention relates to steam-boilers; and its object is to improve and create a greater natural draft, whereby steam can be generated more quickly and rapidly, while a poorer quality of fuel may be employed without the aid of a blower and with good results.

To this end my invention consists in the construction and combination of devices hereinafter set forth and claimed.

The drawings herein shown represent, in 25 Figure 1, a front end elevation of a boiler containing my improvements, with one-half the front plate removed. Fig. 2 is a central vertical section longitudinally of the boiler. Fig. 3 is a sectional plan view showing the 30 position of the transverse draft-flues in the boiler beneath the grate-bars.

As before premised, my improvements are herein applied to an annular boiler, shown as an entirety at 2, and composed of two cylindrical shells—an outer and inner one, respectively—3 4, circular in cross-section. These shells, together with the front and rear end heads, 5 6, form the water-space, which, for convenience of description, may be said 35 to consist of an upper and lower portion, determined by a plane drawn horizontally across the top of the grate-bars 7 7, which are interiorly located or within the bore of the inner shell, 4. As this particular boiler is a horizontal return-flue boiler, flues 8 8 are disposed in the usual manner longitudinally within the water-space and connect with the main stack 9.

To the rear of the grate-bars and interiorly 50 of the water-space rises the "bridge-wall" 10, so called, which rests upon the inner shell, 4, and is made hollow, having air-pas-

sages 12, which extend through the lower water-space and connect with the ash-chamber.

One object in my invention is to prevent 55 the excessive heat and overheating of the grate-bars, ash-chamber, and the adjacent parts, as now frequently occur; hence when the lower door leading to the ash-pit is opened the sudden rush of cool air therein 60 forces the hot air outwardly back upon itself, in lieu of drawing it up through the grate-bars and fire. The draft is thereby checked temporarily. To obviate this overheating I have located the grate-bars within 65 the central bore of the boiler 2, a short distance above the lower water-space of the boiler, which extends therebeneath and forms an ash-chamber, 13. Access to the latter is had by means of the door 14; access to the 70 fire by means of the door 15. Furthermore, exteriorly of the boiler is disposed a jacket or iron plate, 16; circular in cross-section. (See Fig. 1.) This plate beneath the boiler extends from the front of the latter rearwardly therebeneath to a point behind but 75 vertically below the bridge-wall. The chamber so formed I term the "lower ash-chamber," 17. This is separated from the upper flue-space, 21, hereinafter described, by two 80 longitudinal partitions, 20, which unite the outer shell, 3, of the boiler with the external plate, 16. Access to said chamber 17 is had by means of the door 18, which is to be automatically operated by means of some 85 one of the numerous regulators now in use. The upper portion of said plate 16 above and about the boiler extends from the front to the rear of said boiler proper, and forms the flue-passage 21. (See Figs. 1 and 2.) Said 90 passage surrounds the shell 3 of the boiler, and is bounded at the bottom by the longitudinal partitions 20 before mentioned.

To economize fuel and obtain heating-power from the hot gases passing to the stack, I have 95 placed above the shell 3 and between the latter and the external shell, 16, a deflector-plate, 23. Thus the hot gases passing through the return-flues 8 8 and escaping to the stack are turned downward and compelled to pass 100 laterally of the boiler in lieu of directly on top. The path of the gases diverted by the deflector 23 is indicated by arrows *x x* in both drawings.

Communication between the upper and lower ash-chambers is obtained by a series of air-flues, 19 19, arranged transversely across the lower water-space of the boiler, and which 5 connect the inner and outer shells of the boiler at this point. In the present instance there are three rows, with the flues in the several rows alternating. Moreover, said flues are of sufficient diameter to admit passage of 10 any cinder which may drop through the grate-bars.

The fire is tended through the door 15, while the inner surface, 4, of the boiler-shell, or that adjacent to and beneath the grate-bars, 15 is kept free from ashes by a utensil to be inserted through the door 14. The accumulated ashes in the lower chamber, 17, are removed by way of the door 18, which is normally maintained open, the intermediate door, 14, 20 being open only when cleansing the inner shell, 4, or when first starting the fire, when the lowest door, 18, may be shut.

During active service of the boiler the air-currents therethrough are indicated by the 25 arrows, first, by way of the door 18 to ash-chamber 17; thence through the lower water-space, transversely thereof, by way of the air-flues 19 into the upper ash-chamber, 13, and between the grate-bars to the fire. From there 30 the products of combustion are conducted in the usual manner over the bridge-wall, returned through the flues 8 8, thence upwardly and over the crown-sheet to the main stack.

When the fire is first started, the intermediate door, 14, may be opened, but subsequently to be closed, when the lowest door is 35 then employed to regulate the draft. By this construction the draft is increased. The parts surrounding the grate-bars are not liable to 40 become overheated. Furthermore, the inner shell, 4, of the boiler beneath the grate-bars is readily cleansed, while the ashes which pass into the chamber below are readily removed.

The system of pipes herein shown at the rear of the boiler for increasing the circulation is explained and described in an application, Serial No. 280,479, filed July 20, 1888; hence I do not desire to make any claim therefor, but simply show them in connection with my present improvements. 45

50 What I desire to claim is—

1. The combination, in a steam-boiler having an annular water-space, of a hollow bridge-wall interiorly of said water-space, an ash-chamber exteriorly of said water-space, and 55 air-passages 12, extending thereacross, which connect said ash-chamber with the chamber in the bridge-wall, substantially as specified.

2. In a steam-boiler having an annular water-space with draft-flues 8 8 longitudinally 60 therethrough, the combination, with said boiler, of the grate 7, the hollow bridge-wall 10, the air-passage 12, the draft-flues 19 19 transversely of the lower water-space, the ash-chamber 17 below the same, and the doors 65 14 18, the latter operating automatically, substantially as and for the purposes set forth.

3. The combination, with a boiler constructed with an inner shell, 4, an outer shell, 3, composing the water-space, and with the flues 8 8 70 therein, of the transverse draft-flues 19 19 exterior to and below the grate, the grate-bars 7 7, arranged above the lower water-space, and the plate 16, inclosing the outer shell, 3, and forming beneath the said shell the ash-chamber 17, and above and about said shell 75 the flue 21, substantially as herein described.

In testimony whereof I affix my signature in presence of two witnesses.

ANDRIAN I. BARRANOFF.
